UNITED STATES PATENT OFFICE.

HARVEY A. MOYER, OF SYRACUSE, NEW YORK.

DESIGN FOR A THILL-COUPING.

SPECIFICATION forming part of Design No. 35,054, dated September 3, 1901.

Application filed August 5, 1901. Serial No. 70,984. Term of patent 14 years.

To all whom it may concern:

Be it known that I, HARVEY A. MOYER, a citizen of the United States, and a resident of Syracuse, in the county of Onondaga, in the State of New York, have invented a new and original Design for a Thill-Coupling, of which the following, taken in connection with the accompanying drawings, is a full, clear, and exact description.

Figure 1 is a side view of a thill-coupling, showing my design; and Fig. 2 is a front end view of the same.

As shown in the drawings, the leading or material features of my design consist of the peculiar shapes of the base A and its cap B upon the front end portion of said base. The minor peculiarities of the shape of said base are the horizontal top *a* of the rear end portion thereof, terminating in the vertical upward offset *b*, from whence it is curved upward, as shown at *c*, at the end of which the top is formed with a segmental depression *d* and with the short straight portion *e*, terminating in another segmental depression *f*. The more important feature of my design is the shape of the under side of the base A, which is formed with the horizontal rear end portion *g*, at the forward end of which it is curved arch shape, as shown at *h*, and thence

formed with downward tongue-shaped extensions *i*, between the lower ends of which is a transverse bar *j*. These extensions *i*, with the transverse bar *j*, constitute the salient and most important feature of my design. The front end portion of the under side is curved upwardly and forwardly from the extensions *i*, as shown at *l*, and terminates at the front edge of the segmental depression *f* in the top of the said base. The cap B has its front end curved, as shown at *n*, corresponding to the depression *f*, in which it lies. Said end of the cap is perforated at *o*. The bottom of the cap is formed with the segmental recess *p* near the center of its length and is thence curved rearward and upward, as shown at *r*. The top of the cap is curved upward and rearward from the end *n* and thence downward and upward, as shown at *t*, and meets the rear end of the bottom portion *r*.

Having described my design, what I claim as new, and desire to secure by Letters Patent, is—

The design for a thill-coupling as herein shown and described.

HARVEY A. MOYER. [L. S.]
